A. H. HUMPHREY

METHOD OF MANUFACTURING RADIATING ELEMENTS FOR GAS HEATERS

Filed Feb. 15, 1921

INVENTOR.
Alfred H. Humphrey
Chappell & Earl
ATTORNEYS.

UNITED STATES PATENT OFFICE.

ALFRED H. HUMPHREY, OF NEW YORK, N. Y., ASSIGNOR TO GENERAL GAS LIGHT COMPANY, OF KALAMAZOO, MICHIGAN.

METHOD OF MANUFACTURING RADIATING ELEMENTS FOR GAS HEATERS.

Application filed February 15, 1921. Serial No. 445,182.

To all whom it may concern:

Be it known that I, ALFRED H. HUMPHREY, a citizen of the United States, residing at the city and county of New York, State of New York, have invented certain new and useful Improvements in Methods of Manufacturing Radiating Elements for Gas Heaters, of which the following is a specification.

10 This invention relates to improvements in method of manufacturing radiating elements for gas heaters.

The main objects of this invention are: 15 to provide an improved method of manufacturing radiating elements for gas heaters.

Further objects, and objects relating to structural details, will definitely appear from the detailed description to follow.

20 I accomplish the objects of my invention by the devices and means described in the following specification. The invention is clearly defined and pointed out in the claim.

A structure which is a preferred embodiment of my invention is clearly illustrated 25 in the accompanying drawing, forming a part of this specification, in which:

Fig. I is a front view of a completed radiating element embodying the features of my invention.

30 Fig. II is an inside view of the front and back portions formed in the process of manufacture.

Fig. III is a bottom view.

Fig. IV is a plan view of the female members of the mold illustrating the process of manufacture.

Fig. V is a plan view of the front mold.

Fig. VI is a detail section on a line corresponding to line 6—6 of Fig. IV further illustrating the method of manufacture.

Fig. VII is a detail section corresponding to that of Fig. VI showing another step in the process of manufacture.

Fig. VIII is an enlarged detail front elevation still further illustrating the method of manufacture.

In the drawing similar reference characters refer to similar parts throughout the several views, and the sectional views are taken looking in the direction of the little arrows at the ends of the section lines.

Referring to the drawing, my improved radiating element, as illustrated, consists of a front portion 1 and a complementary back portion 2. These front and back portions

are formed in molds 3 and 4, respectively, from earthy material and their edges 5 and 6 pressed together while still in the plastic state and united by firing. The front and rear portions are of suitable openwork and 60 are preferably provided with inwardly projecting spurs 7.

The material from which the parts are molded is preferably in the form of strips 8 of uncolored earthy material which is laid 65 upon the molds, as illustrated in Figs. IV and VI, and pressed into the mold by the male mold members 9.

The face of the radiating element is shaded or partially colored, as at 10, by embedding therein granules 11 of colored earthy material. This is effected by sprinkling the granular colored material into the molds and pressing the plastic strips thereon, thereby embedding the colored material 75 so that when the element is fired it becomes an integral part thereof.

I thus produce radiating elements having shaded or partially colored front surfaces, the remainder of the elements being uncolored. This is of material advantage in radiating elements which are very neat and attractive in appearance and, further, the discolorations of age or use are not apparent. The surface thus colored does not 85 detract from the radiating quality or the incandescent glow of the main or body portion of the element.

Having thus described my invention, what I claim as new and desire to secure by 90 Letters Patent, is:

The method of manufacturing tubular foraminated radiating elements for gas heaters consisting of molding complementary front and back portions from uncolored plastic material and embedding in the surface of the front portions granules of colored earthen material, said front and back portions being otherwise uncolored providing uncolored rear and inner surfaces, 100 joining the front and back portions while plastic, and firing.

In witness whereof, I have hereunto set my hand and seal in the presence of two witnesses.

ALFRED H. HUMPHREY. [L.S.]

Witnesses:

ANNIE E. PARRY,
HATTIE V. SAXTON.
